UNITED STATES PATENT OFFICE.

WILLIAM DUKE, OF LONGTOWN, ASSIGNOR OF ONE-HALF TO EDMUND G. GRAHAM, OF COLDWATER, MISSISSIPPI.

BALING-PRESS.

SPECIFICATION forming part of Letters Patent No. 234,549, dated November 16, 1880.

Application filed March 12, 1880. (No model.)

To all whom it may concern:

Be it known that I, WILLIAM DUKE, of Longtown, in the county of Panola and State of Mississippi, have invented a new and useful Improvement in Baling-Presses, of which the following is a specification.

Figure 1 is a sectional elevation of the improvement. Fig. 2 is a plan view of the lower grooved plate. Fig. 3 is a plan view of the friction-plate.

The object of this invention is to improve the construction of the baling-presses for which Letters Patent No. 100,687 were granted March 8, 1870, in such manner as to lessen the friction, and thus allow the presses to be operated with a less expenditure of power.

The invention consists in constructing a rotating baling-press with plates and rollers interposed between its friction-surfaces to diminish the friction when the press is operated, as will be hereinafter fully described.

Similar letters of reference indicate corresponding parts.

A represents the frame of the press, which frame is provided with a baling-box, B, doors C, and a platform, D, as shown and described in Letters Patent No. 100,687. In the center of the base of the frame A is formed a screw-hole, E, or to the said base-frame is attached a nut to receive the screw F, the lower end of which has a square foot, G, formed upon or rigidly attached to it, to fit into the square cavity of the well H. The well H is formed of timbers placed in a hole in the ground, and has a frame, I, attached to its upper end, to rest upon the ground and receive the downward pressure of the press.

To the upper end of the well H, or to the ground-frame I, is attached a plate or block, J, through which the screw F passes. In the upper side of the plate or block J is formed a groove, K, which is made with vertical sides and an outwardly-inclined bottom, to receive the conical friction-rollers L, the inclination of the bottom of the groove K being such that the upper side of the rollers L will be horizontal. Upon the rollers L rests a plate, M, attached to the base of the frame A, and through which the screw F passes. If desired, the

plate M may be the faced lower side of the nut E when a nut is used.

The upper end or head of the screw F is made square to fit into a square recess in the lower side of the block or plate N, so as to hold the said block or plate N from turning. In the upper side of the block or plate N is formed a ring-groove, O, which is made with vertical sides and an outwardly-inclined bottom, and which is designed to receive the conical friction-rollers P. Upon the upper side of the rollers P rests the faced lower side, Q, of the follower R, or a plate attached to the said lower side of the follower R.

To the lower part of the frame A are attached one or more levers, S, to which the power may be applied; or the power may be applied to a gear-wheel or pulley, T, attached to the base of the frame A.

The press may be operated by hand, by horse-power, by steam-power, or by any other convenient power.

With this construction, when the frame A is rotated, the screw F will be raised by the revolution of the nut E, forcing the follower R upward and compressing the material in the baling-box into a bale, the frame A being made sufficiently heavy to prevent it from moving up upon the screw F.

With this construction the friction from the rotation of the frame A will be very greatly reduced, thus removing the objection to the press described in Letters Patent No. 100,687.

If desired, the friction-rollers L P may be made in spherical form, in which case the bottoms of the grooves K O should be horizontal.

I am aware that it is not new to use conical rolls on inclined faces, a follower-screw, or a well for the screw; but

What I claim is—

In a baling-press, the combination, with the follower-screw F G, of the well H, ground-frame I, having apertured block J, with inclined groove K, the conical friction-rolls L, and the plate M, as shown and described.

WILLIAM DUKE.
